CLAIM

The ornamental design for an electric vehicle charger, as shown and described.

DESCRIPTION

FIG. 1 is a perspective view of a left top side of an electric vehicle charger showing our new design;
FIG. 2 is a perspective view of a right bottom side thereof;
FIG. 3 is a front elevational view thereof;
FIG. 4 is a left side elevational view thereof. The right side is a mirror image of the left side;

FIG. 5 is a top plan view thereof; and,
FIG. 6 is a bottom plan view thereof.

The phantom lines shown in FIGS. 1-6 are included for the purpose of illustrating environmental structure and form no part of the claimed design.
